UNIT FOR TOY VEHICLES

Filed Jan. 25, 1933

UNITED STATES PATENT OFFICE

HARRY T. KINGSBURY, OF KEENE, NEW HAMPSHIRE, ASSIGNOR TO KINGSBURY MFG. COMPANY, OF KEENE, NEW HAMPSHIRE, A CORPORATION OF NEW HAMPSHIRE

UNIT FOR TOY VEHICLES

Application filed January 25, 1933. Serial No. 653,543.

This invention relates to improvements in structural elements for toy vehicles and more particularly to a combined axle support and bumper unit adapted to be used as a swivel 5 frame on toy automobiles.

An object of the present invention is to provide a combined front axle support and bumper unit for a toy automobile wherein the entire unit is secured to the chassis of 10 the automobile for turning movement about a fixed point.

A further object of the invention is to provide a combined axle support and bumper unit which may be formed from a single metal 15 blank.

A still further object of the invention is to provide a unit, of the type referred to, wherein the unit is secured to the chassis member of a toy automobile at a single point 20 and adapted to turn about this point and wherein means are provided for preventing the bending of the unit and for limiting the turning movement about the pivot point.

A further object of the invention is to provide 25 a unit, of the type referred to, wherein means are provided for frictionally holding the said unit in any position to which it may be turned by an operator.

The invention still further aims to provide 30 a unit for toy vehicles, of the type referred to, which is inexpensive to manufacture, which is easily applied to a toy automobile, and which is strong and durable.

These and other objects of the invention 35 will be obvious and will be hereinafter more fully described.

In the drawing:—

Figure 1 is a plan view of the blank before the forming operations.

Fig. 2 is a similar view showing a further step in the forming operations.

Fig. 3 is a rear end view showing the ends of the bumper portion curved.

Fig. 4 is a top plan view of the completed 45 unit.

Fig. 5 is a bottom plan view of the completed unit as applied to the chassis of a toy automobile.

Fig. 6 is a sectional view of the unit, taken 50 along line 6—6 of Fig. 4, and showing a por-

tion of the automobile chassis with the unit applied thereto.

The invention aims generally to provide a structural unit adapted to be used with toy automobiles or the like. The unit comprises 55 a combined front axle support and bumper which may or may not be formed from a single metal blank. The unit is secured to the under surface of the chassis of a toy automobile at one point so that the entire unit 60 is rotated when the wheels are turned for steering.

Referring, in detail, to the accompanying drawing, a metal blank 10, as shown in Fig. 1, is provided with a main body portion 11 to 65 which is secured a bumper portion 12 by spaced connecting arms 13, 13^a. The body portion is provided with oppositely disposed ear portions 14, 14^a which extend outwardly from the body portion adjacent the connecting arms 13, 13^a. A centrally located portion 15 extends from the body portion 11 forwardly between the connecting arms 13, 13^a. A lip portion 16, which is centrally 70 located with respect to the ear portions 14, 14^a, extends rearwardly from the body portion 11. The bumper portion 12 is provided with openings 17 to give a more realistic appearance. The edges 18, 19, 18^a, 19^a of the connecting arm 13, 13^a, respectively, are 75 adapted to be bent downwardly whereby to strengthen the unit, as shown in Figs. 4, 5 and 6.

The ear portion 14 is provided with an opening 20 while the ear portion 14^a is provided with a slot 20^a. An offset tongue member 21 is provided in the body portion 11 of the blank 10. This tongue member 21 is centrally located and extends toward the rear of the unit. The lip portion 16 is punched 80 or otherwise machined to provide an eyelet or flanged opening 22 centrally located therein. The lip portion is then slightly offset, as shown at 23 in Figs. 4, 5 and 6, so that it is raised slightly above the plane of the body portion 11 of the blank 10. Raised portions 24, 24^a forming ribs are provided in the body portion 11 by a suitable forming operation. These ribs are symmetrically located at an angle to the edge of the rear of the body 85 90 95 100

portion and are of a height substantially even with the top surface of the lip portion 16 which has been slightly offset from the body portion, as shown in Fig. 6.

5 The edges 18, 18^a of the connecting arms 13, 13^a respectively are bent downwardly along the dotted line *c*, in Fig. 1, to a portion substantially at right angles to the connecting arms. At the same time, the portion 15 is bent downwardly along dotted line *c* to a position substantially at right angles to the body portion 11 of the blank 10. In this manner, a continuous depending edge is provided around the connecting arms and the 15 body portion 11. The ear portions 14, 14^a and the opposite edges 19, 19^a of the connecting arms respectively are bent downwardly substantially along dotted lines *d* and *d'* respectively. The edges 19, 19^a are bent at right angles to the connecting arms while the ear portions are only bent at acute angles to the plane of the body portion 11 of the blank. The end portions 25, 25^a of the ears 14, 14^a wherein are located the opening 20 and the slot 20^a respectively are again bent to a position substantially at right angles to the body portion 11 so that the portions 25, 25^a are in parallel relation whereby the opening 20 and the slot 20^a are in axial alignment. The bumper portion 12 is bent downwardly along dotted lines *f* and *f'* to a position, as shown in Fig. 4.

The completed unit is illustrated in Fig. 4 before being applied to a toy automobile. 35 The unit will now be described in the application thereof to the front of a toy automobile, as shown in Figs. 5 and 6, wherein is shown a portion of the front of a chassis 26 of a toy automobile having the usual front 40 fenders 27 secured thereto. A front axle 28 is adapted to have one end thereof pass through the opening 20 in the depending portion 25 of the ear 14 and to have the other end thereof pass through the slot 20^a in the 45 depending portion 25^a of the ear 14^a. Wheels 29 are secured to the ends of the axle 28, as shown in Fig. 5. The slot 20^a permits a limited amount of vertical movement of the axle 28 therein so that both wheels will rest upon 50 the surface upon which the toy is placed. The chassis 26 is provided with a radiator section 30. A portion of the chassis midway between the fenders 27 is cut out to provide an arcuate front edge 31 on the front of the 55 chassis and straight edge portions 32, 32^a which extend forwardly from the arcuate edge 31 to the radiator section 30. The flange formed around the opening 22 is passed through an opening in the chassis member 26 60 midway between the sides thereof and is then spun over the chassis, as shown at 33 in Fig. 6, whereby to hold the unit in rotatable engagement with said chassis. Every point on the arcuate edge 31 is equidistant from the 65 center of the opening 22 after the unit is se-

cured to the chassis. The tongue member 21 is adapted to overlap the top surface of the chassis 26, as shown in Fig. 6, whereby to prevent the unit from bending downwardly.

70 The tongue member 21 passes over the arcuate edge 31 as the unit is turned for steering and is adapted to prevent the turning of the unit beyond a position obtained when the tongue member meets either of the straight edge portions 32, 32^a on the chassis. 75 The ribs 24, 24^a are adapted to frictionally contact with the under surface of the chassis since they are of the same height above the body portion 11 as is the top surface of the offset lip portion 16. These ribs, therefore, tend to resist slightly the turning of the unit so that it will remain in any position in which it is turned by the operator.

80 It is, of course, obvious that the bumper portion 12 and the body portion 11 may be made from separate blanks and later secured together to provide the completed axle support and bumper unit. It will be seen that a compact unit is herein provided and one which is inexpensively manufactured and readily applied to the chassis of a toy automobile. As has heretofore been pointed out and described, novel means are provided for securing the unit to the chassis and for preventing the same from bending. The unit is also provided with the tongue portion 21 which cooperates with the modified structure of the chassis 26 in order to prevent the unit from turning more than a predetermined distance in either direction.

85 Of course, minor changes in details of construction and manner of application may be made without departing from the scope of the invention as set forth in the appended claims.

90 Having thus fully described my invention, what I claim as new and desire to secure by Letters Patent, is:—

1. A blank consisting of a single sheet of metal adapted to be formed into a combined axle support and bumper for a toy automobile, said blank comprising a body portion having oppositely disposed projecting portions, arms forwardly extending from said body portion, and a bumper section connected with and extending transversely across the ends of said arms.

110 2. A blank adapted to be formed into a combined axle support and bumper for a toy automobile, said blank comprising a body portion having oppositely disposed ear portions with openings therein and adapted to be bent downwardly, arms forwardly extending from said body portion, and a bumper section secured to said arms and adapted to be bent downwardly.

115 3. A blank adapted to be formed into a combined axle support and bumper for a toy automobile, said blank comprising a body portion having oppositely disposed ear por-

tions adapted to be bent downwardly and being provided with openings therein to support an axle, an offset portion extending rearwardly from said body portion and being 5 slightly above the horizontal surface thereof, rib portions on said body portion of a height substantially even with said offset portion, connecting arms extending forwardly from said body portion, and a bumper portion secured to said arms and adapted to be bent downwardly and curved at the ends thereof.

4. The combination of a toy vehicle having a chassis, said chassis having a centrally located cut out portion in the front thereof, 15 the rear edge of said cut out portion being arcuate in shape, and a unit adapted to be secured to said chassis centrally of the sides thereof, said unit including a body portion having depending ear portions to support an axle, 20 ribs on said body portion adapted to frictionally engage the under surface of said chassis, a tongue member on said body portion adapted to overlap said arcuate edge, and a bumper portion secured to said body portion.

25 5. A structural unit for toy vehicles comprising a body portion having depending portions adapted to support an axle, arms forwardly extending from said body portion, a bumper member secured to said arms, said 30 body portion having a depending edge portion opposite said bumper member and adapted to merge into the inner edges of said arms.

6. A structural unit adapted to be secured to the chassis of a toy vehicle for turning 35 movement, said unit comprising a body portion having depending portions adapted to support an axle, said body portion having an offset portion to which the chassis is secured, and a bumper member secured to said body 40 portion.

7. A structural unit adapted to be secured to the chassis of a toy vehicle for turning movement, said unit comprising a body portion having depending portions adapted to 45 support an axle, said body portion adapted to be secured to the chassis, raised portions on said body portion adapted to frictionally engage said chassis, and a bumper member secured to said body portion.

50 8. A structural unit adapted to be secured to the chassis of a toy vehicle, said unit comprising a body portion having depending parallel portions adapted to support an axle and an offset portion to which the chassis is 55 secured, raised portions on said body portion, said raised portions adapted to frictionally engage the chassis, and a bumper member secured to said body portion.

9. A structural unit adapted to be secured to the chassis of a toy vehicle, said unit comprising a body portion having depending ear portions adapted to support an axle, an offset surface on said body portion adapted to be secured to the chassis, and raised portions 60 on said body portion adapted to frictionally

engage the under face of said chassis, said raised portions being substantially equal in height to said offset surface.

10. The combination of a toy vehicle having a chassis, said chassis having an arcuate front edge portion, and a unit adapted to be secured to said chassis centrally of the sides thereof for turning movement, said unit including a body portion having depending ear portions adapted to support an axle, a tongue member on said body portion adapted to overlap said arcuate front edge portion and a bumper member secured to said body portion.

11. The combination of a toy vehicle having a chassis, said chassis having a front edge 80 portion and a unit adapted to be secured to said chassis centrally of the sides thereof, said unit including a body portion having depending portions adapted to support an axle, ribs on said body portion adapted to 85 frictionally engage the surface of said chassis, and a bumper member secured to said body portion.

12. A structural unit adapted to be mounted for turning movement on the chassis of a 90 toy vehicle, said unit comprising a body portion having depending portions adapted to support an axle, and raised portions on said body portions, said raised portions adapted to frictionally engage the surface of said 95 chassis.

13. A structural unit adapted to be mounted for turning movement on the chassis of a toy vehicle, said unit comprising a body portion having depending portions adapted to 100 support an axle, a tongue member adapted to overlap an edge of said chassis, and rib portions adapted to frictionally engage the surface of said chassis.

14. A structural unit adapted to be mounted for turning movement on the chassis of a toy vehicle, said unit comprising a body portion having depending ears adapted to support an axle, a raised portion on said body portion centrally located with respect to said 110 depending ears and adapted to be secured to said chassis for rotation centrally of the sides thereof, and means for providing a friction contact at spaced intervals between said chassis and said body portion.

15. The combination of a toy vehicle having a chassis and a unit adapted to be used in connection therewith, said unit comprising a body portion having depending ears adapted to support an axle, means for securing said unit to said chassis for turning movement, and means for providing spaced friction surfaces between said chassis and said body portion.

16. A structural unit for toy vehicles having a chassis, said unit comprising a body portion having depending ears adapted to support an axle, a raised portion on said body portion centrally located with respect to said 125 depending ears and adapted to be secured to 130

said chassis for turning movement centrally of the sides thereof, means providing a friction contact at spaced intervals between said chassis and said body portion, and a bumper portion secured to said body portion.

17. The combination of a toy vehicle having a chassis and a unit adapted to be used in connection therewith, said unit comprising a body portion having depending ears adapt-

ed to carry an axle, means for securing said unit to said chassis for turning movement, means providing spaced friction surfaces between said chassis and said body portion, and a bumper member secured to said body portion.

In testimony whereof, I affix my signature.

HARRY T. KINGSBURY.
